UNITED STATES PATENT OFFICE

2,201,512

AUTOMATIC CONTROL FOR TOY ELECTRIC TRAINS

Clyde J. R. Witman, Pottsville, Pa.

Application December 19, 1938, Serial No. 246,741

2 Claims. (Cl. 246—31)

This invention relates to toy electric trains and has for an object to provide apparatus for automatically controlling two or more toy electric trains so that they will start and stop without 5 the possibility of wrecks or collisions.

A further object is to provide a novel track layout comprising preferably a main endless track and spaced transverse tracks within the enclosure of the endless track, in combination with 10 magnetically operated switches of conventional type known by the trade name of "Lionel," operating to direct two or more trains in such manner that the trains will travel alternately along the track layout, one train being halted while the 15 other is running, and the running train at a point in its travel operating to start the halted train on its journey just prior to the running train coming to a stop.

A further object is to provide a device of this 20 character which may be readily constructed of conventional parts, and which will not easily get out of order.

With the above and other objects in view the invention consists of certain novel details of 25 construction and combinations of parts herein-after fully described and claimed, it being understood that various modifications may be resorted to within the scope of the appended claims without departing from the spirit or sacrificing 30 any of the advantages of the invention.

In the accompanying drawings forming part 35 of this specification:

Figure 1 is a diagrammatic view showing the 40 track layout, switches, and magnetic controlling devices.

Figure 2 is a longitudinal sectional view of one 45 of the controlling solenoid devices.

Figure 3 is a cross sectional view taken on the 50 line 3—3 of Figure 2 with parts removed.

Figure 4 is a plan view of one of the distant 55 control track switches of conventional type.

Referring now to the drawings in which like 60 characters of reference designate similar parts in the various views, 10 designates the main endless track of a toy electric railroad, and 11 and 12 designate two spaced transverse branch tracks, this layout being illustrative, it being optional to use as many branch tracks as desired. There 65 are three rails as usual constituting each track, an outer rail 13, an inner rail 14, and an intermediate rail 15. The invention contemplates forming insulated sections on these rails upon which trains come to a halt, there being three 70 such insulated sections shown in the present embodiment at 16, 17 and 18, the insulated sec- 75

tion 16 being formed on one end transverse portion of the main endless track and the insulated sections 17 and 18 being formed on the branch tracks, all of the insulated sections being parallel to each other. Each insulated section is formed by interpolating in the inner rail a pair of spaced blocks 19 of insulating material and interpolating in the intermediate rail a pair of spaced blocks 20 of insulating material opposite the blocks 19. 10

Included in the construction of the track layout are a plurality of pressure operated electric switches 21, 22 and 23, interposed in the transverse end portion of the main track and in the two branch tracks in advance of the insulated 15 sections, by "advance" meaning in the direction of a train traveling counterclockwise along the track layout as indicated by the arrowheads. The pressure operated switches are of the conventional type comprising a hinged section of the 20 track forming a circuit closer and moving the circuit closer to circuit closing position by the weight of the engine of the toy train, as the toy train passes thereover.

Incorporated in the main track at the entrance 25 to the transverse branch tracks are respective distant control switches 24 and 25 of the conventional type which may be identified by the catalog number 223, manufactured by the Lionel Corporation and covered, I believe, by Patent 1,671,- 30 236, issued May 29, 1928.

Also incorporated in the main track at the exits of the branch track are respective distant control switches 26 and 27 also identified by the catalog number 223 issued by the Lionel Corpora- 35

The automatic control apparatus comprises a plurality of solenoid type electric switches 28, 29 and 30 corresponding to the three insulated sections of the track layout, shown diagrammatically in Figure 1 and shown somewhat in detail in Figures 2 and 3. 40

Each solenoid type electric switch is provided with two coils 31 and 32 mounted on an insulating base 33 which latter carries two pairs of spaced stationary switch contacts 34 and 35. The core 36 is provided with an arm 37 of insulating material which carries a pair of spaced bridging switch contacts 38 and 39 which are moved by the selectively energized coils 31 and 32 45 to bridge a respective pair of the contacts 35—34 and be yieldably held in circuit closing position through the medium of a spring 40 which is connected to the arm 37 and base 33. Stops 41 and 42 are disposed in the path of movement 50

55

of the core 36 to limit movement thereof in either direction.

A transformer 43 furnishes the current supply, the transformer having taps 44 to deliver suitable voltage preferably within the range of 10 to 30 volts.

In wiring the apparatus the transformer is connected by wires 45 and 46 to the intermediate track rail 15 and the outer track rail 13 respectively. A wire 47 is connected to the wire 45 and to the movable contact of each of the three pressure operated switches 21, 22 and 23. A wire 48 is connected to the fixed switch contact of each of the three pressure operated switches 15 and to this latter wire a wire 49 is connected which leads to a terminal 50 on the mounting base 33 of the three solenoid type electric switches 28, 29 and 30. A wire 52 is connected to the wire 45 and to a terminal 53 on the base 33. Thus the current from the transformer is divided, part passing to the pressure operated switches 21, 22 and 23, part passing to the intermediate rail 15 and part passing to the three solenoid type electric switches 28, 29 and 30.

The purpose of the solenoids and their connections to the dead sections 16, 17 and 18 of the track layout is to permit a train passing over one of the pressure operated switches, prior to coming to rest in a dead section, as train #2 is shown in the diagram, energizing a dead section as for example, the dead section 17, to permit the train thereon to start on its journey as shown by train #1 which has just left the dead section 17 while train #2 has come to rest in the dead section 16.

The pressure controlled switches are so wired to the automatic control switch that any of the pressure controlled switches can operate any one of the solenoids. The train on the dead section 40 of the track is the selective operator of the solenoid. The wiring diagram is shown in Figure 1.

The inner rails 14 of the dead sections 16, 17 and 18 of the track are connected by respective wires 54, 56 and 58 to one end of the front coil 32 of the respective solenoids 30, 28 and 28.

The intermediate rails 15 of the dead sections are connected by respective wires 55, 57 and 59 to one of the front contacts 35 of the respective solenoids 30, 28 and 28 and to the front end of the rear coil 31 of these solenoids.

A wire 60 is connected to the transformer terminal 53 and to the other front contacts 35 of the solenoids 28, 29 and 30 and supplies current to these contacts, which contacts, as before explained, are connected to the front end of the rear coil 31 of the solenoids.

A wire 61 is connected to the rear end of the rear coils 31 of these solenoids and is connected by a wire 62 to a reset switch 63, for all the solenoids, located on the main endless track in advance of the last dead section 18.

When a train passes over the reset switch 63, any solenoid which is set with its bridging switch contact 39 cross-connecting the two front contacts 35, as shown by the position of the intermediate solenoids 29, will be moved to the other position to dispose the bridging switch contact to engage the rear contacts 38, by energizing of the rear coil 31 of that solenoid by operation of the reset switch.

One of the rear contacts 34 of each solenoid is connected by a wire 64 to the terminal 50 which, as before stated, is connected to the wire 49 leading from the pressure operated switches 21, 22 and 23. The other rear contact is connected by

a wire 65 to the rear end of the front coil 32 of the respective relay.

In operation, when a train passes over a pressure operated switch the current flows to the solenoid 32 through the wire 49, wire 61, one rear contact 34, rear bridging switch contact 38, to the rear contact 34 which is connected to the rear of the solenoid 32. However, the core will not move until current has been supplied to the other end of the solenoid 32. This current must come from the outer track rail 13 and pass through the locomotive, which is the selector, to the intermediate track rail 15, to wire 54, 56 or 58, whichever the case may be, to the respective solenoid 32. When that selected solenoid is energized its core is moved and moves the front bridging switch contact 39 into circuit closing position on the front contacts 35 of said solenoid, in which position the respective wires 55, 57 and 59, whichever the case may be, are energized to put in motion the train on the respective dead section of the track.

When any train reaches the reset switch 63 the switch is operated to energize the rear solenoid 31 whose front bridging contact is in circuit closing position to retract the core thereof and move the rear bridging switch contact 38 into circuit closing position on the rear contacts 34 and reset the solenoid switch for the next actuation which has been described above.

There is no predetermined rotation of the solenoids. A train can be taken off the track entirely and replaced in most any part of the layout and be able to continue its rotation as if it had never been disturbed. This can only be done by the current flowing through the locomotive.

From the above it is thought that it will be clear how the movements of the trains are automatically controlled by the pressure operated switches, solenoid switches and reset switch, without further explanation.

For controlling the trains manually a manually operable switch 66 which is connected to the wire 52 and wire 49 on the other side of the terminals 50 and 53 from the solenoids 28, 29 and 30.

From the above description it is thought that the construction and operation of the invention will be fully understood without further explanation.

What is claimed is:

1. Control apparatus for toy electric trains comprising a main substantially oblong track and spaced transverse branch tracks within the enclosure of the main track, each track having three rails, insulated sections on the rails of the transverse end portions of the main track and on the rails of each transverse branch tracks upon which trains are brought to a halt for a time period, pressure operated electric switches interposed in the transverse end portion of the main track and in the branch tracks in advance of the insulated sections of the tracks and closed by trains passing thereover, electrically controlled switches incorporated in the main track at the entrance to the transverse branch tracks for directing trains into the branch tracks, electrically controlled switches incorporated in the main track at the exits of the branch track for directing trains into the main track, a current supply connected in circuit with the intermediate track rail and the outer track rail of the tracks and connected in circuit with each of the pressure operated switches, and solenoid switches connected in circuit with the source of electricity each having two coils and a movable contact and

- pairs of fixed contacts forming two circuit closing positions, the coils and fixed contacts of each solenoid being connected in circuit with a pressure operated switch in such manner as to energize an insulated section of the track to permit the train halted thereon to proceed therefrom simultaneously with a predetermined pressure operated switch being closed by a train passing thereover.
- 5 2. Control apparatus for toy electric trains comprising a main substantially oblong track and spaced transverse branch tracks within the enclosure of the endless track, each track having three rails, insulated sections on the rails of the transverse end portions of the main track and on the rails of the branch tracks upon which toy trains are brought to a halt for a time period, pressure operated electric switches interposed in the transverse end portion of the main track and 10 in the branch tracks in advance of the insulated sections of the tracks and closed by trains pass-
- ing thereover, a current supply connected in circuit with the intermediate track rail and the outer track rail of the tracks and connected in circuit with each of the pressure operated switches, solenoid switches connected in circuit with the source of electricity each having two coils and a movable contact and pairs of fixed contacts forming two circuit closing positions, the coils and fixed contacts of each solenoid being connected in circuit with a pressure operated switch in such manner as to energize an insulated section of the track to permit the train halted thereon to proceed therefrom simultaneously with a predetermined pressure operated switch being closed by a train passing thereover, and a 15 reset switch incorporated in the main track and connected in circuit with certain of the coils of the solenoid switches and operated by a train passing thereover to reset the solenoid switches after each actuation. 20
